(57) **ABSTRACT**

A printing apparatus includes a printing head including a nozzle configured to discharge ink, and a control unit configured to control the printing head to print a test pattern on a printing medium, for inspecting a state of ink discharge by the nozzle. The test pattern includes a pattern element formed by a plurality of dots of the ink, and the control unit causes the printing head to print the test pattern where a number of the dots forming the pattern element on a second printing medium is smaller than a number of the dots forming the pattern element on a first printing medium, the second printing medium being more susceptible to bleed-through of the ink than the first printing medium.

PRINTING APPARATUS AND PRINTING METHOD

The present application is based on, and claims priority from JP Application Serial Number 2020-112569, filed Jun. 30, 2020, the disclosure of which is hereby incorporated by reference herein in its entirety.

BACKGROUND

1. Technical Field

The present disclosure relates to a printing apparatus and a printing method.

2. Related Art

Technology has been disclosed of an inkjet type printing apparatus in which a test pattern is printed on a print sheet by a recording head, the test pattern is read by a scanner, interpolation processing is performed on read data, and a nozzle abnormality is determined on the basis of the interpolated read data (see JP-A-2007-54970).

However, when a medium is selected, as a printing medium used for printing, in which ink bleed-through occurs relatively easily, the ink bleeds through and spreads, the shape of each of elements configuring the test pattern becomes uneven, and as a result, inspection of the nozzle on the basis of the read data of the test pattern cannot be appropriately performed. Thus, there is a need for a suitable test pattern for appropriately performing the inspection of the nozzle.

SUMMARY

A printing apparatus includes a printing head including a nozzle configured to discharge ink, and a control unit configured to control the printing head to print a test pattern on a printing medium, for inspecting a state of ink discharge by the nozzle. The test pattern includes a pattern element formed by a plurality of dots of the ink, and the control unit causes the printing head to print the test pattern where a number of the dots forming the pattern element on a second printing medium is smaller than a number of the dots forming the pattern element on a first printing medium, the second printing medium being more susceptible to bleed-through of the ink than the first printing medium.

A printing method includes a printing step of printing a test pattern on a printing medium, using a printing head including a nozzle configured to discharge ink, for inspecting a state of ink discharge by the nozzle. The test pattern includes a pattern element formed by a plurality of dots of the ink, and the printing step causes the printing head to print the test pattern where a number of the dots forming the pattern element on a second printing medium is smaller than a number of the dots forming the pattern element on a first printing medium, the second printing medium being more susceptible to bleed-through of the ink than the first printing medium.

BRIEF DESCRIPTION OF THE DRAWINGS

FIG. 1 is a block diagram illustrating a device configuration in a simplified manner.

FIG. 2 is a diagram illustrating a specific example of a configuration including a transport unit and a printing head.

FIG. 3 is a view illustrating a relationship between the printing medium and the printing head, as seen from above.

FIG. 4 is a flowchart illustrating a flow from TP printing to an inspection of nozzles.

FIG. 5 is a diagram illustrating an example of TP image data.

FIG. 6 is a diagram illustrating an enlarged portion of a TP.

FIG. 7 is a diagram illustrating an example of a medium-specific dot count table.

FIG. 8 is a diagram illustrating an example of a dot count table.

FIG. 9 is a diagram illustrating TP image data according to a modified example.

DESCRIPTION OF EXEMPLARY EMBODIMENTS

Embodiments of the present disclosure will be described below with reference to the accompanying drawings. Note that each of the drawings is merely illustrative for describing the embodiment. Since the drawings are illustrative, proportions and shapes may not be precise, match each other, or some may be omitted.

1. APPARATUS CONFIGURATION

FIG. 1 illustrates a configuration of a printing apparatus 10 according to the embodiment, in a simplified manner.

The printing apparatus 10 is provided with a control unit 11, a display unit 13, an operation receiving unit 14, a communication IF 15, a transport unit 16, a carriage 17, a printing head 18, a reading unit 19, and the like. IF is an abbreviation for interface. The control unit 11 is configured to include, as a processor, one or more ICs including a CPU 11a, a ROM 11b, a RAM 11c, and the like, another non-volatile memory, and the like.

In the control unit 11, the processor, that is, the CPU 11a executes arithmetic processing in accordance with one or more programs 12 stored in the ROM lib, the other memory, or the like, using the RAM 11c or the like as a work area, to realize various functions such as a printing control unit 12a, a reading control unit 12b, an inspection unit 12c, and the like. Note that the processor is not limited to the single CPU, and a configuration may be adopted in which the processing is performed by a hardware circuit such as a plurality of CPUs, an ASIC, or the like, or a configuration may be adopted in which the CPU and the hardware circuit work in concert to perform the processing.

The display unit 13 is a device for displaying visual information, and is configured, for example, by a liquid crystal display, an organic EL display, or the like. The display unit 13 may be configured to include a display and a drive circuit for driving the display. The operation receiving unit 14 is a device for receiving an operation by a user, and is realized, for example, by a physical button, a touch panel, a mouse, a keyboard, or the like. Of course, the touch panel may be realized as a function of the display unit 13.

The display unit 13 and the operation receiving unit 14 may be part of the configuration of the printing apparatus 10, or may be peripheral devices externally coupled to the printing apparatus 10. The communication IF 15 is a generic term for one or a plurality of IFs for coupling the printing apparatus 10 with the outside in a wired or wireless manner, in accordance with a prescribed communication protocol including a known communication standard provide.

The transport unit 16 is a device for transporting the printing medium, and includes a roller, a motor for rotating the roller, and the like. The printing head 18 ejects ink from nozzles onto the printing medium, using an inkjet method, to perform printing. The reading unit 19 is a device for reading a printing result on the printing medium. The reading unit 19 is also referred to as a scanner. However, the printing apparatus 10 may have a configuration that does not include the reading unit 19.

The carriage 17 is a mechanism capable of reciprocating along a predetermined direction as a result of receiving power from a carriage motor (not illustrated). The predetermined direction in which the carriage 17 moves is referred to as a main scanning direction. As illustrated in FIG. 2 and FIG. 3, the printing head 18 is mounted on the carriage 17.

The configuration of the printing apparatus 10 illustrated in FIG. 1 may be realized by a single printer, or may be realized by a plurality of communicatively coupled devices.

In other words, the printing apparatus 10 may be the printing system 10 in actuality. The printing system 10 includes, for example, an information processing device that functions as the control unit 11, and a printer including the transport unit 16, the carriage 17, the printing head 18, and further, the reading unit 19. A printing method according to the embodiment is realized in this way by the printing apparatus 10 or the printing system 10.

Further, a portion of the control unit 11 that functions as the printing control unit 12a and a portion of the control unit 11 that functions as the reading control unit 12b and the inspection unit 12c may be separate information processing devices.

FIG. 2 illustrates a specific example of a configuration mainly including the transport unit 16 and the printing head 18, which are part of the printing apparatus 10. In FIG. 2, the specific example is illustrated using a perspective orthogonal to a transport direction D2 of a printing medium 30.

The transport unit 16 is provided with a feeding shaft 22 upstream in the transport direction, and a winding shaft 25 downstream in the transport direction. Upstream and downstream in the transport direction are simply denoted using upstream and downstream. The long printing medium 30 wound in a roll shape around the feeding shaft 22 and the winding shaft 25 is stretched along the transport direction D2. The printing medium 30 is transported in the transport direction D2. The printing medium 30 may be a paper sheet or may be a medium made from a material other than paper.

In the example illustrated in FIG. 2, the printing medium 30 wound around the feeding shaft 22 is fed downstream by the feeding shaft 22 rotating in the clockwise direction. A front driving roller 23 is provided at a position downstream of the feeding shaft 22, and a rear driving roller 24 is provided at a position upstream of the winding shaft 25. By rotating in the clockwise direction, the front driving roller 23 transports downstream the printing medium 30 fed out from the feeding unit 22. A nip roller 23n is provided with respect to the front driving roller 23. The nip roller 23n comes into contact with the printing medium 30 so as to clamp the printing medium 30 between the nip roller 23n and the front driving roller 23.

By rotating in the clockwise direction, the rear driving roller 24 transports further downstream the printing medium 30 transported downstream by the front driving roller 23. Note that a nip roller 24n is provided with respect to the rear driving roller 24. The nip roller 24n comes into contact with the printing medium 30 so as to clamp the printing medium 30 between the nip roller 24n and the rear driving roller 24.

The printing head 18 that discharges ink onto the printing medium 30 from above is disposed between the front driving roller 23 and the rear driving roller 24. As illustrated in FIG. 2, the printing head 18 is mounted on the carriage 17. The printing head 18 is capable of discharging a plurality of colors of ink, such as cyan (C), magenta (M), yellow (Y), black (K), light cyan (LC), and light magenta (LM), for example.

Each of the nozzles of the printing head 18 is open in a nozzle surface 20, of the printing head 18, facing the printing medium 30, and the printing head 18 discharges or does not discharge the ink from the nozzles on the basis of print data. The ink discharged by the nozzle is also referred to as an ink droplet, or as a dot. The printing head 18 may also be referred to as a print head, an inkjet head, a liquid discharging head, a recording head, and the like.

As a result of the winding shaft 25 rotating in the clockwise direction, the winding shaft 25 takes up the printing medium 30 after printing that is transported by the rear driving roller 24.

The feeding shaft 22, the winding shaft 25, each of the rollers, the motor (not illustrated) for rotating these members as appropriate, and the like are a specific example of the transport unit 16 that transports the printing medium 30. A number and arrangement of the rollers provided along the transport path for transporting the printing medium 30 is not limited to the mode illustrated in FIG. 2. Further, the colors of the inks discharged by the printing head 18 are not limited to the colors described above. It goes without saying that a flat platen or the like, which supports, from below, the printing medium 30 that receives the ink discharge from the printing head 18, may be provided between the front driving roller 23 and the rear driving roller 24. Further, the portion of the printing medium 30 on which the printing by the printing head 18 has been performed need not necessarily be wound into the roll shape by the winding shaft 25, and may be cut away from the printing medium 30 that is upstream of the printed portion, using a cutter (not illustrated).

In the example illustrated in FIG. 2, the reading unit 19 is provided at a position downstream of the carriage 17 and the printing head 18 and upstream of the rear driving roller 24. Using an image sensor, the reading unit 19 optically reads the printing medium 30 on which the printing has been performed by the printing head 18, and outputs image data as a reading result. The reading unit 19 may be configured to read the printing medium 30 while being moved by the carriage in a similar manner to the printing head 18, or may be configured to read the printing medium 30 in a stationary state.

FIG. 3 illustrates a relationship between the printing medium 30 and the printing head 18 in a simplified manner, as seen from above. The printing head 18 mounted on the carriage 17 moves, together with the carriage 17, from one end of a main scanning direction D1 to the other end (a forward movement) and from the other end to the one end (a return movement). The main scanning direction D1 and the transport direction D2 intersect each other. The intersection may be understood to be orthogonal. Accordingly, FIG. 2 illustrates the printing head 18 and the like from a perspective facing in the main scanning direction D1. However, due to various errors in the printer as a manufactured product, for example, the main scanning direction D1 and the transport direction D2 may not be precisely orthogonal.

In FIG. 3, an example is illustrated of an array of nozzles 21 in the nozzle surface 20. Each of small circles in the nozzle surface 20 is the nozzle 21. The printing head 18 is provided with a plurality of nozzle rows 26 in a configura-

tion in which each color of the inks is discharged from the nozzles **21** after being supplied from a liquid holding unit (not illustrated) that is referred to as an ink cartridge, an ink tank, or the like. The nozzle row **26** including the nozzles **21** that discharge the C ink is also described as a nozzle row **26C**. Similarly, the nozzle row **26** including the nozzles **21** that discharge the M ink is also described as a nozzle row **26M**, the nozzle row **26** including the nozzles **21** that discharge the Y ink is also described as a nozzle row **26Y**, the nozzle row **26** including the nozzles **21** that discharge the K ink is also described as a nozzle row **26K**, the nozzle row **26** including the nozzles **21** that discharge the LC ink is also described as a nozzle row **26LC**, and the nozzle row **26** including the nozzles **21** that discharge the LM ink is also described as a nozzle row **26LM**. The nozzle rows **26C**, **26M**, **26Y**, **26K**, **26LC**, and **26LM** are aligned along the main scanning direction **D1**.

Each of the nozzle rows **26** is configured by the plurality of nozzles **21** for which a nozzle pitch, which is an interval between the nozzles **21** in the transport direction **D2**, is constant or substantially constant. The direction in which the plurality of nozzles **21** configuring the nozzle row **26** are aligned is referred to as a nozzle row direction **D3**. In the example illustrated in FIG. 3, the nozzle row direction **D3** is parallel with the transport direction **D2**. In the configuration in which the nozzle row direction **D3** is parallel with the transport direction **D2**, the nozzle row direction **D3** and the main scanning direction **D1** are orthogonal. However, the nozzle row direction **D3** need not necessarily be parallel with the transport direction **D2**, and a configuration may be adopted in which the nozzle row direction **D3** obliquely intersects the main scanning direction **D1**.

The respective positions of the nozzle rows **26C**, **26M**, **26Y**, **26K**, **26LC**, and **26LM** in the transport direction **D2** match each other. The printing apparatus **10** prints an image on the printing medium **30** by performing a combination of transport of the printing medium **30** in the transport direction **D2**, and ink discharge by the printing head **18** in accordance with movement of the carriage **17** along the main scanning direction **D1**. The operation of the ink discharge by the printing head **18** in accordance with the forward movement and the return movement of the carriage **17** is referred to as a “scan” or a “pass”. The movement of the printing head **18** in the main scanning direction **D1** by the carriage **17** corresponds to one of relative movements between the printing head **18** and the printing medium **30**.

2. TEST PATTERN PRINTING

FIG. 4 illustrates, using a flowchart, a flow executed by the control unit **11** in accordance with the program **12**, from printing of a TP to an inspection of the nozzles **21** on the basis of the TP. TP is an abbreviation for test pattern. The flowchart consists, in overview, of TP printing processing (step **S100**), acquisition of a reading result of the printed TP (step **S200**), and an inspection based on the reading result of the TP (step **S300**). Step **S100** corresponds to a TP printing step. In FIG. 4, step **S100** is illustrated in detail while being divided into steps **S110** to **S150**.

At step **S110**, the printing control unit **12a** acquires TP image data, which is image data representing the TP, from a storage source such as a predetermined memory or storage device with which the control unit **11** can communicate. The TP image data is, for example, image data in a bitmap format defining the color of each of pixels in a predetermined color system. As the color system referred to here, for example,

there are various color systems, such as an RGB (red, green, blue) color system, a CMYK color system, or the like.

At step **S120**, the printing control unit **12a** sets TP printing conditions. The printing control unit **12a** sets the printing conditions when performing normal printing as the TP printing conditions. The normal printing refers to a process in which an object such as a photo, text, CG, or the like chosen by the user is printed, rather than the TP. The user can set the printing conditions for the normal printing by operating the operation receiving unit **14** while viewing a user interface (UI) screen displayed on the display unit **13**. The printing conditions include, for example, the type of the printing medium **30** and a printing quality.

There are various types of the printing medium **30** such as, for example, coated paper to which a glossy coating material is applied and having a high degree of glossiness, matte paper having a lower degree of glossiness than that of the coated paper, plain paper, and the like. The coated paper is also referred to as gloss coated paper, or as glossy paper. The user sets the desired type of the printing medium **30** in the transport unit **16**, and sets the type of the set printing medium **30** as an item of the printing conditions. In the embodiment, when the type of the printing medium **30** is referred to as a “first printing medium”, the printing medium **30** that is more susceptible to ink bleed-through than the first printing medium, is referred to as a “second printing medium”. In other words, in the embodiment, the difference in the type of the printing medium **30** is captured as a difference in the susceptibility of the printing medium **30** to the bleed-through of the ink. As an example, when the coated paper is the first printing medium, that matte paper corresponds to the second printing medium. Note that the printing control unit **12a** may set the type of the printing medium **30** as the item of the printing conditions by automatically determining the type of the printing medium **30** on the basis of data acquired by sensing the printing medium **30** set on the printing apparatus **10**, using a sensor or a scanner.

The print quality is presented to the user as subjective options, such as high resolution, normal, fast, and the like, and the printing control unit **12a** sets each of items necessary for execution of the printing in accordance with the selected printing quality, such as a movement velocity of the carriage **17**, a transport velocity of the transport unit **16**, a waveform of drive signals used to drive the nozzles **21**, and a driving period of the nozzles **21** in the pass. Further, if a default setting is provided for the printing conditions, and the user does not specifically change the default setting, the printing control unit **12a** applies the default setting to the TP printing or the normal printing.

The order of execution of steps **S110** and **S120** may be reversed from that illustrated in FIG. 4, or may be substantially simultaneous.

At step **S130**, the printing control unit **12a** generates the print data for the TP printing, from the TP image data. The printing control unit **12a** generates the print data that prescribes ink discharge (dot on) or ink non-discharge (dot off) for each of the pixels and each of the ink colors, by performing predetermined image processing, such as color conversion processing and halftone processing, on the TP image data. As illustrated in FIG. 3, assuming that the printing head **18** uses the six colors of ink of CMYKLCM, at step **S130**, the printing control unit **12a** generates the print data prescribing the dot on and off for each of the pixels and for each of CMYKLCM, based on the TP image data.

FIG. 5 illustrates an example of TP image data **40** acquired at step **S110**. The TP image data **40** is image data representing a TP **41**. In FIG. 5, and FIG. 6 to be described

below, a correspondence relationship between the TP image data 40 and the directions D1 and D2 is also illustrated. The TP 41 includes a TP for each of the ink colors. According to FIG. 5, a TP 41C is the TP represented by the color C. Similarly, a TP 41LC is the TP of the LC color, a TP 41M is the TP of the M color, a TP 41LM is the TP of the LM color, a TP 41Y is the TP of the Y color, and a TP 41K is the TP of the K color.

In the TP image data 40, the TPs 41C, 41LC, 41M, 41LM, 41Y, and 41K for each of the ink colors are aligned in the main scanning direction D1, and the positions thereof in the transport direction D2 are the same as each other. Each of the TPs 41C, 41LC, 41M, 41LM, 41Y, and 41K for each of the ink colors is a collection of a plurality of "pattern elements". In the example illustrated in FIG. 5, each of the pattern elements is a ruled line parallel to the main scanning direction D1. Each one of the pattern elements is an image printed using one of the nozzles 21 of the corresponding ink color.

FIG. 6 illustrates an enlarged portion of the TP 41 represented by the TP image data 40. Specifically, FIG. 6 illustrates portions of the TP 41C and the TP 41LC, respectively. The TP 41C is configured by a plurality of pattern elements 42C arranged at equal intervals in the transport direction D2, and the TP 41LC is configured by a plurality of pattern elements 42LC arranged at equal intervals in the transport direction D2. In FIG. 6, for ease of understanding, as well as the TPs 41C and 41LC, a portion of each of the nozzle rows 26C and 26LC used for printing the TPs 41C and 41LC are also illustrated. In other words, each of the pattern elements 42C is disposed at a spacing similar to the nozzle pitch in the transport direction D2, such that each one of the pattern elements 42C configuring the TP 41C is printed by one of the nozzles 21 configuring the nozzle row 26C. Similarly, each of the pattern elements 42LC is arranged at a spacing similar to the nozzle pitch in the transport direction D2, such that each one of the pattern elements 42LC configuring the TP 41LC is printed by one of the nozzles 21 configuring the nozzle row 26LC.

Further, in the example illustrated in FIG. 6, in order to easily verify each one of these pattern elements 42C at the time of inspection, each of the pattern elements 42C is disposed with a position thereof being offset in the main scanning direction D1, such that the positions thereof in the main scanning direction D1 coincide every three cycles. Similarly, each of the pattern elements 42LC is also disposed with a position thereof being offset in the main scanning direction D1, such that the positions thereof in the main scanning direction D1 coincide every three cycles. However, the pattern elements configuring the TP corresponding to one of the ink colors may all have the same position in the main scanning direction D1.

Further, in the example illustrated in FIG. 6, the pattern elements 42C and the pattern elements 42LC are disposed with the positions thereof offset in the main scanning direction D1 in order to reduce the bleed-through of each one of the pattern elements 42C and the pattern elements 42LC. For example, when the pattern element 42C is printed in two passes, the dots printed in a first pass are disposed at odd-numbered pixel positions in the main scanning direction D1, and the dots printed in a second pass are disposed at even-numbered pixel positions in the main scanning direction D1. Further, for example, when the pattern elements 42LC are printed in two passes, the dots printed in the first pass are disposed at the odd-numbered pixel positions in the main scanning direction D1, and the dots printed in the second pass are disposed at the even-numbered pixel posi-

tions in the main scanning direction D1. However, when printing on the printing medium 30 in which bleed-through is not likely to occur, the dots may be formed in all of the pixels in each pass.

5 The print data generated at step S130 is image data in which the TP 41 represented by the TP image data 40 is expressed using the dot on and off. Each of the pattern elements configuring each of the TPs 41C, 41LC, 41M, 41LM, 41Y, and 41K for each of the ink colors is formed of 10 dots of the corresponding ink color only.

At step S140, the printing control unit 12a determines, depending on the type of the printing medium 30, a number of passes and a thinning ratio when printing the TP. The type of the printing medium 30 referred to here is the type of the 15 printing medium 30 set as the item of the printing conditions at step S120. The printing control unit 12a determines a common number of passes and thinning ratio for the TPs 41C, 41LC, 41M, 41LM, 41Y, and 41K.

FIG. 7 illustrates an example of a medium-specific dot 20 count table 50. The medium-specific dot number table 50 is stored in advance in a memory or a storage device, either in or outside the printing apparatus 10, so as to be accessible by the control unit 11. The medium-specific dot count table 50 is a table defining parameters used to determine, directly or indirectly, the number of dots for printing the TP depending on the type of the printing medium 30. According to FIG. 25 7, the medium-specific dot count table 50 prescribes the number of passes and the thinning ratio for each of the coated paper and the matte paper. It goes without saying that 30 the medium-specific dot count table 50 may be a table prescribing the number of passes and the thinning ratio for other types of the printing medium in addition to the coated paper and the matte paper. At step S140, the printing control unit 12a refers to the medium-specific dot count table 50, to 35 determine the number of passes and the thinning ratio depending on the type of the printing medium 30 set at step S120.

The number of passes is the number of the passes used to 40 print the TP. For example, if the number of passes is 2 for a given type of the printing medium 30, this does not mean that the TP 41 represented by the print data generated at step S130 is printed in two passes, but that the pass to print the TP 41 represented by the print data is repeated twice. Thus, 45 the greater the number of passes, the greater the number of dots forming the pattern elements in the TP 41 reproduced on the printing medium 30. According to the medium-specific dot count table 50, the printing control unit 12a determines that the number of passes is 2 when the type of the printing medium 30 is the coated paper, and determines 50 that the number of passes is 1 when the type of the printing medium 30 is the matte paper.

The thinning ratio is the thinning ratio in a single pass. For 55 example, when the thinning ratio relating to the type of the printing medium 30 is 50%, in one pass, during a period for printing the TP 41 represented by the print data generated at step S130, regardless of whether the original dot is dot on or dot off, for 50% of the pixels, dot off is forcibly applied and the ink is not discharged. Therefore, the higher the thinning ratio, the fewer the number of dots forming the pattern 60 elements in the TP 41 reproduced on the printing medium 30. Further, it can be said that the higher the thinning ratio, the more a discharge rate of the ink by the nozzle 21 is reduced, and the lower the thinning ratio, the more the discharge rate of the ink by the nozzle 21 is increased. Thus, 65 by changing the thinning ratio depending on the type of the printing medium 30, the discharge rate of the nozzles 21 can be controlled for each type of the printing medium 30.

According to the medium-specific dot count table 50, the printing control unit 12a determines that the thinning ratio is 50% when the type of the printing medium 30 is the coated paper, and determines that the thinning ratio is 66% when the type of the printing medium 30 is the matte paper. When the thinning ratio is 0%, this means that the printing is performed as per the print data for each of the passes.

Here, in the print data generated at step S130, it is assumed that all of the individual pattern elements that configure any of the TPs 41C, 41LC, 41M, 41LM, 41Y, and 41K for each of the ink colors is configured by approximately the same number of dots. According to step S140 at which the medium-specific dot count table 50 is referred to, when the type of the printing medium 30 is the coated paper that is the first printing medium, the number of passes is determined to be 2 and the thinning ratio is determined to be 50%. When the type of the printing medium 30 is the matte paper that is the second printing medium, the number of passes is determined to be 1 and the thinning ratio is determined to be 66%. As a result, when comparing the number of dots of the pattern elements printed on the matte paper with the number of dots of the pattern elements printed on the coated paper based on the determination at step S140, the number of dots of the C ink forming the one pattern element 42C printed on the matte paper, for example, is approximately one third the number of dots of the C ink forming the one pattern element 42C printed on the coated paper.

At step S150, the printing control unit 12a prints the TP 41 on the printing medium 30 by controlling the movement of the carriage 17 and the ink discharge by the printing head 18, in accordance with the printing conditions set at step S120, the print data generated at step S130, and the number of passes and the thinning ratio determined at step S140.

Specifically, when the type of the printing medium 30 is the coated paper, based on the medium-specific dot count table 50, the printing head 18 performs two passes to print the TP 41 on the printing medium 30. In each of the two passes, the printing head 18 discharges the CMYKLCLM inks from the respective nozzles 21 of the nozzle rows 26C, 26LC, 26M, 26LM, 26Y, and 26K to print the TPs 41C, 41LC, 41M, 41LM, 41Y, and 41K on the basis of the print data and at the thinning ratio of 50%.

On the other hand, when the type of the printing medium 30 is the matte paper, the printing head 18 performs one pass to print the TP 41 on the printing medium 30. The printing head 18 discharges the CMYKLCLM inks from the respective nozzles 21 of the nozzle rows 26C, 26LC, 26M, 26LM, 26Y, and 26K to print the TPs 41C, 41LC, 41M, 41LM, 41Y, and 41K on the basis of the print data and at the thinning ratio of 66%.

As a result, when performing a comparison at a pattern element level, the printing control unit 12a has printed the TP 41 such that the number of dots forming the pattern element on the second printing medium is less than the number of dots forming the pattern element on the first printing medium. Note that the printing control unit 12a does not cause the transport unit 16 to transport the printing medium 30 during a period of time from a first pass for the printing head 18 to print the TP 41 to the end of a last pass.

The above is a description of step S100. Steps S200 and S300 will be briefly described.

At step S200, the reading control unit 12b controls the reading unit 19 to read the printing medium 30 on which the TP 41 has been printed at step S100, and retrieves the image data from the reading unit 19 as the reading result. It goes without saying that the transport unit 16 performs the

transport necessary for the reading unit 19 to read the printing medium 30 after the printing.

However, at step S200, it is sufficient that the reading result of the printing medium 30 on which the TP 41 has been printed can be acquired. Thus, the user may cause an external scanner to read the printing medium 30 on which the TP 41 has been printed, and the printing apparatus 10 may acquire the reading result via the communication IF 15.

At step S300, the inspection unit 12c inspects a state of the ink discharge by the nozzles 21 of the printing head 18, based on the image data acquired as the reading result at step S200. The state of the ink discharge is divided into normal and abnormal. Abnormal applies to a discharge failure in which the dot cannot be discharged, landing position displacement in which the landing positions of the dots are displaced from ideal landing positions, and the like. The inspection unit 12c inspects whether each of the nozzles 21 is normal or abnormal by analyzing the image data and identifying a density and position of each of the pattern elements for each of the ink colors and for each of the nozzles 21, and stores inspection results as data.

The flowchart illustrated in FIG. 4 ends here.

3. SUMMARY AND DESCRIPTION OF EFFECTS

As described above, according to the embodiment, the printing apparatus 10 includes the printing head 18 including the nozzles 21 that discharge the ink, and the control unit 11 that, by controlling the printing head 18, causes the TP to be printed on the printing medium 30 for the inspection of the state of the ink discharge by the nozzles 21. The TP includes the pattern elements formed of the plurality of dots of the ink. Then, the control unit 11 reduces the number of dots forming the pattern element in the TP printed by the printing head 18 on the second recording medium for which the bleed-through of the ink is likely to occur in comparison to the number of dots forming the pattern element in the TP printed by the printing head 18 on the first printing medium. In other words, the control unit 11 causes the printing head 18 to print the TP so as to reduce the number of dots forming the pattern element on the second printing medium in comparison to the number of dots forming the pattern element on the first printing medium.

According to the configuration, when printing the TP on the second printing medium, the pattern element is printed using fewer dots than when the TP is printed on the first printing medium. In this way, as a printing result of the TP on the second printing medium, the TP can be provided including each of the pattern elements in which the bleed-through is suppressed. As a result, when printing the TP on the printing medium 30 for which the ink bleed-through is likely to occur, a problem is avoided that is caused by a shape of the pattern element becoming uneven due to the ink bleed-through, and the inspection on the reading result cannot be appropriately performed. Specifically, with the pattern elements whose shape has become uneven due to the ink bleed-through, since it is difficult to accurately identify a position and the like when performing the inspection based on the reading result, the above-described determination as to whether the ink discharge is normal or abnormal cannot be performed with a high degree of accuracy. However, by performing the printing of the TP at step S100 of the embodiment, whichever of the printing medium 30 is used, the inspection of the nozzles 21 using the pattern elements can be performed with a high degree of accuracy.

11

Further, according to the embodiment, the printing head **18** is capable of performing the scan that discharges the ink from the nozzles **21** as the printing head **18** moves in the predetermined direction, and the control unit **11** reduces the number of scans for printing the pattern element on the second printing medium in comparison to the number of scans for printing the pattern element on the first printing medium. In other words, the control unit **11** causes the printing head **18** to print the TP with a reduced number of scans for printing the pattern element on the second printing medium, in comparison to the number of scans for printing the pattern element on the first printing medium.

According to the configuration, by causing the number of scans for printing the pattern elements on the second printing medium to be fewer than the number of scans for printing the pattern elements on the first printing medium, the control unit **11** can easily print the TP in which the number of dots forming the pattern elements on the second printing medium are fewer than the number of dots forming the pattern elements on the first printing medium.

Further, according to the embodiment, the control unit **11** may reduce the discharge rate of the ink by the nozzles **21** for printing the pattern elements on the second printing medium in comparison to the discharge rate of the ink by the nozzles **21** for printing the pattern elements on the first printing medium. In other words, the control unit **11** causes the printing head **18** to print the TP while lowering the ink discharge rate of the ink by the nozzles **21** for printing the pattern elements on the second printing medium in comparison to the discharge rate of the ink by the nozzles **21** for printing the pattern elements on the first printing medium.

According to the configuration, by causing the discharge rate of the ink by the nozzles **21** for printing the pattern elements on the second printing medium to be lower than the discharge rate of the ink by the nozzles **21** for printing the pattern elements on the first printing medium, the control unit **11** can easily print the TP in which the number of dots forming the pattern elements on the second printing medium are fewer than the number of dots forming the pattern elements on the first printing medium.

The number of passes and numerical values of the thinning ratio for each of the types of the printing medium **30** in the medium-specific dot number table **50** illustrated in FIG. 7 are merely examples. Further, the medium-specific dot count table **50** may be, for example, a table in which the number of passes is the same regardless of the type of the printing medium **30**, and the difference between the first printing medium and the second printing medium is provided in terms of the thinning ratio. Alternatively, the medium-specific dot count table **50** may be a table in which the thinning ratio is the same regardless of the type of the printing medium **30**, and the difference between the first printing medium and the second printing medium is provided in terms of the number of passes.

Further, according to the embodiment, the printing conditions when printing the TP are the same as the printing conditions when performing the normal printing.

In other words, the control unit **11** sets a velocity of a relative movement between the printing head **18** and the printing medium **30** when printing the TP to be the same as the velocity of the relative movement when performing the normal printing. According to the above description, the velocity of the relative movement referred to here is the movement velocity of the carriage **17** when performing the pass.

Further, the control unit **11** sets a waveform of a drive signal used to drive the nozzle **21** when printing the TP to be

12

the same as the waveform of the drive signal used to drive the nozzle **21** when performing the normal printing. The drive signal used to drive the nozzle **21** is a pulse wave, and the drive signal is applied to a driving element of each of the nozzles **21** in accordance with the dot on information, thus causing the dot to be discharged from the nozzle **21**. If the waveform of the drive signal is different, a size of the dot discharged by the nozzle **21** in a single drive is also different.

In this way, by setting the velocity of the relative movement and the drive signal to be the same for the printing of the TP and for the normal printing, the TP suitable for performing the inspection of the nozzle **21** can be printed under the same conditions as when performing the normal printing.

15 The embodiment also discloses an invention of each of categories, such as a method other than the printing apparatus **10** and the printing system **10**, and the program **12**.

The printing method includes the printing step of printing the TP on the printing medium **30**, using the printing head **18** including the nozzles **21** that discharge the ink, for inspecting the state of the ink discharge by the nozzles **21**. The TP includes the pattern elements formed by the plurality of dots of the ink, and the printing step causes the printing head **18** to print the TP where the number of the dots forming the pattern element on the second printing medium is smaller than the number of the dots forming the pattern element on the first printing medium.

4. OTHER EMBODIMENTS

30 The embodiment is not limited to the modes described above.

Specific examples of the first printing medium and the second printing medium are not limited to the types described above. For example, when the matte paper is assumed to be the first printing medium, the plain paper may be the second printing medium. Further, for the coated paper, the matte paper, the plain paper, and other printing media, the printing apparatus **10** may print the TP such that the number of dots per pattern element is reduced the more the printing medium used is susceptible to the bleed-through of the ink.

45 The printing apparatus **10** need not necessarily be a so-called serial inkjet printer in which the printing head **18** is mounted on the carriage **17** that moves in the main scanning direction **D1**, as described above.

A so-called line type inkjet printer for discharging the ink may be assumed, using the printing head **18** including the nozzle rows **26** for each of the ink colors, where the nozzle rows **26** extend in the main scanning direction **D1** intersecting the transport direction **D2** and are long enough to cover the width of the printing medium **30**. In the line type inkjet printer, the nozzle row direction **D3** may be understood to be parallel with the main scanning direction **D1** rather than with the transport direction **D2**.

50 When describing the embodiment assuming that the printing apparatus **10** is the line type inkjet printer, the TP **41** is printed on the printing medium **30** such that the TP **41** has an orientation in which each of the pattern elements, which 55 is the ruled line, is parallel with the transport direction **D2** rather than with the main scanning direction **D1**. Further, the plurality of passes of the printing head **18** described above are achieved using back feed by the transport unit **16**. The back feed is processing in which the transport unit **16** transports the printing medium **30** from downstream to upstream. In other words, when the printing medium **30** passes under the printing head **18** in the process of trans-

porting the printing medium **30** from upstream to downstream, printing is performed once on the printing medium **30**. Thereafter, the transport unit **16** returns the portion of the printing medium **30** that has once been printed, back to a position upstream of the printing head **18**, and once more starts transporting the printing medium **30** downstream. By repeating this, the TP **41** can be repeatedly printed in the same manner as the serial inkjet printer prints the TP **41** in the superimposed manner by the plurality of passes.

When the printing apparatus **10** is the line type inkjet printer, the transport of the printing medium **30** by the transport unit **16** during the printing period by the printing head **18** corresponds to the relative movement between the printing head **18** and the printing medium **30**. In other words, when the printing apparatus **10** is the line type inkjet printer, the transport velocity of the transport unit **16** during the printing period by the printing head **18** is the same when printing the TP and when performing the normal printing.

It goes without saying that the printing medium **30** need not necessarily be the continuous sheet wound into the roll, as exemplified in FIG. 2, or the like. The printing medium **30** may be a single sheet cut into page units, or the like.

5. MODIFIED EXAMPLES

In addition to the type of printing medium **30** described above, the printing apparatus **10** may print the TP by varying the number of dots configuring the pattern element in accordance with a difference in ink color or a difference in dot size.

The TP includes a “first ink pattern element” formed by a plurality of dots of a “first ink” and a “second ink pattern element” formed by a plurality of dots of a “second ink” that has a higher degree of brightness than the first ink. For example, assuming that the six color inks of CMYKLCLM are used, the CMYK inks corresponds to the first ink, and the LC and LM inks correspond to the second ink. In FIG. 5, the TPs **41C**, **41M**, **41Y**, and **41K** are the TPs printed using the first ink, and the TPs **41LC** and **41LM** are the TPs printed using the second ink. Further, in FIG. 6, the pattern element **42C** corresponds to an example of the first ink pattern element, and the pattern element **42LC** corresponds to an example of the second ink pattern element. However, the Y ink that has a higher degree of brightness than the CMK inks may be treated as the second ink rather than the first ink. In such a case, the control unit **11** may cause the printing head **18** to print the TP in which the number of dots of the second ink forming the second ink pattern element is higher than the number of dots of the first ink forming the first ink pattern element.

Further, each of the plurality of nozzles **21** may be capable of discharging the dots of a plurality of sizes in which a volume per droplet is different. In the following description, the dot having a given size is referred to as a “first size” dot, and the dot having a size smaller than the first size is referred to as a “second size” dot. For convenience, the first size dot is referred to as a “large dot”, and the second size dot is referred to as a “small dot”. The size of each of the large dot and the small dot is set in terms of design considerations. In such a case, the TP includes a “first size pattern element” formed by a plurality of the dots of the first size and a “second size pattern element” formed by a plurality of the dots of the second size. The control unit **11** may cause the printing head **18** to print the TP in which the number of dots of the second size forming the second size pattern element is higher than the number of dots of the first size forming the first size pattern element. The “large dot,” which is the dot

of the first size, may be formed by discharging a plurality of the “small dots,” which are the dots of the second size.

FIG. 8 illustrates dot count tables **51** and **52**, which are referred to by the printing control unit **12a** at step **S140** in the modified example. The dot count tables **51** and **52** are tables defining parameters for directly or indirectly determining the number of dots for printing the TP, and are stored in advance in a memory or a storage device, either in or outside the printing apparatus **10**, so as to be accessible by the control unit **11**. The dot count table **51** prescribes the number of passes for each type of the printing medium **30**, and for each of the ink colors and for each of the dot sizes. On the other hand, the dot count table **52** prescribes the thinning ratio for each type of the printing medium **30**, and for each of the ink colors and for each of the dot sizes.

FIG. 9 illustrates the TP image data **40** acquired at step **S110** in the modified example. The TP image data **40** is the image data representing the TP **41**. Of the TP **41**, a TP **41C1** printed using the C ink, a TP **41LC1** printed using the LC ink, a TP **41M1** printed using the M ink, a TP **41LM1** printed using the LM ink, a TP **41Y1** printed using the Y ink, and a TP **41K1** printed using the K ink are printed with the large dots of the respectively corresponding colors, and may be understood to be the same as the TPs **41C**, **41LC**, **41M**, **41LM**, **41Y**, and **41K** illustrated in FIG. 5. On the other hand, a TP **41C2** printed using the C ink, a TP **41LC2** printed using the LC ink, a TP **41M2** printed using the M ink, a TP **41LM2** printed using the LM ink, a TP **41Y2** printed using the Y ink, and a TP **41K2** printed using the K ink are printed with the small dots of the respectively corresponding colors. In other words, in the modified example, the TP for each of the ink colors and for each of the dot sizes is printed on the printing medium **30** of the type set by the user.

In FIG. 9, each of the pattern elements configuring the TPs **41C1**, **41M1**, **41Y1**, and **41K1** corresponds to the first ink pattern element and corresponds to the first size pattern element. Each of the pattern elements configuring the TPs **41C2**, **41M2**, **41Y2**, and **41K2** corresponds to the second ink pattern element and corresponds to the second size pattern element.

Each of the pattern elements configuring the TPs **41LC1** and **41LM1** corresponds to the second ink pattern element and corresponds to the first size pattern element.

Each of the pattern elements configuring the TPs **41LC2** and **41LM2** corresponds to the second ink pattern element and corresponds to the second size pattern element.

At step **S140**, in the modified example, by referring to the dot count tables **51** and **52**, the printing control unit **12a** determines the number of passes and the thinning ratio for printing the TP for each of the ink colors and each of the dot sizes depending on the type of the printing medium **30** set at step **S120**.

For example, it is assumed that the type of the printing medium **30** is the coated paper. At this time, according to the dot count tables **51** and **52**, for the K ink and the large dots, that is, for the printing of the TP **41K1**, the printing control unit **12a** determines the number of passes to be 2 and the thinning ratio to be 50%. For the K ink and the small dots, that is, for the printing of the TP **41K2**, the printing control unit **12a** determines the number of passes to be 6, and the thinning ratio to be 0%. Similarly, for the LC ink and the large dots, that is, for the printing of the TP **41LC1**, the printing control unit **12a** determines the number of passes to be 4 and the thinning ratio to be 0%, for example. For the LC ink and the small dots, that is, for the printing of the TP **41LC2**, the printing control unit **12a** determines the number of passes to be 10 and the thinning ratio to be 0%.

15

For example, it is assumed that the type of the printing medium 30 is the matte paper. At this time, according to the dot count tables 51 and 52, for the K ink and the large dots, that is, for the printing of the TP 41K1, the printing control unit 12a determines the number of passes to be 1 and the thinning ratio to be 66%. For the K ink and the small dots, that is, for the printing of the TP 41K2, the printing control unit 12a determines the number of passes to be 4 and the thinning ratio to be 50%. Similarly, for the LC ink and the large dots, that is, for the printing of the TP 41LC1, the printing control unit 12a determines the number of passes to be 2 and the thinning ratio to be 50%, for example. For the LC ink and the small dots, that is, for the printing of the TP 41LC2, the printing control unit 12a determines the number of passes to be 8 and the thinning ratio to be 50%.

According to the dot count tables 51 and 52 described above, when the TP 41 is printed on the coated paper and the TP 41 is printed on the matte paper, under the same ink color and dot size conditions, the number of dots forming the pattern elements of the TP is fewer when using the matte paper. This is the same as the embodiment described with reference to FIG. 7. In addition, according to the dot count tables 51 and 52, for the TP printed using the first ink, such as CMYK, and the TP printed using the second ink, such as LCLM, under the same conditions of the type of the printing medium 30 and the dot size, the number of dots forming the pattern elements of the TP is fewer when using the second ink. Furthermore, according to the dot count tables 51 and 52, for the TP printed using the first size dots (the large dots), and the TP printed using the second size dots (the small dots), under the same conditions of the type of the printing medium 30 and the ink color, the number of dots forming the pattern elements of the TP is fewer when using the second size.

In this way, according to the modified example, the control unit 11 causes the number of dots forming the pattern element in the TP, which is printed by causing the printing head 18 to perform the printing on the second printing medium, to be fewer than the number of dots forming the pattern element in the TP, which is printed by causing the printing head 18 to perform the printing on the first printing medium, and causes the number of dots of the second ink forming the second ink pattern element to be greater than the number of dots of the first ink forming the first ink pattern element.

According to this configuration, the second ink pattern element printed using the ink of a color having a high degree of brightness can also be printed with a certain degree of density. As a result, even when a difference in brightness is small between the printing medium 30 and a portion, of the TP for inspecting each of the nozzles 21, printed using some of the inks having the high degree of brightness, a failure resulting from not being able to appropriately perform the inspection based on the reading result of the reading can be eliminated. Specifically, for the pattern element having the small difference in brightness with the printing medium 30 that is white or of a color having a high degree of brightness, it is difficult to accurately identify the position and the like of the pattern element at the time of the inspection based on the reading result. Thus, the determination relating to normal or abnormal as described above cannot be performed with a high degree of accuracy. However, using the TP printed at step S100 of the modified example, the nozzle 21 for any of the ink colors can be inspected with a high degree of accuracy based on the pattern element.

Further, according to the modified example, the control unit 11 causes the number of dots forming the pattern

16

element in the TP printed by causing the printing head 18 to perform the printing on the second printing medium to be fewer than the number of dots forming the pattern element in the TP printed by causing the printing head 18 to perform the printing on the first printing medium, and causes the number of dots of the second size forming the second size pattern element to be greater than the number of dots of the first size forming the first size pattern element.

According to this configuration, the second size pattern element printed using the small dot size can also be printed with a certain degree of density. In this way, even when a difference in brightness is small between the printing medium 30 and a portion, of the TP for inspecting each of the nozzles 21, printed using the relatively small dots, the failure resulting from not being able to appropriately perform the inspection based on the reading result of the reading can be eliminated. Specifically, for the pattern element having a small difference in brightness with the printing medium 30 that is white or of a color having a high degree of brightness, it is difficult to accurately identify the position and the like of the pattern element at the time of the inspection based on the reading result. Thus, the determination relating to normal or abnormal as described above cannot be performed with a high degree of accuracy. However, using the TP printed at step S100 of the modified example, the inspection can be performed with a high degree of accuracy based on each of the pattern elements resulting from the discharge of the dots of differing sizes by the nozzles 21.

Furthermore, according to the modified example, when causing the printing head 18 to perform the printing of the TP on the printing medium 30, the control unit 11 causes the number of dots of the second ink forming the second ink pattern element to be greater than the number of dots of the first ink forming the first ink pattern element, and causes the number of dots of the second size forming the second size pattern element to be greater than the number of dots of the first size forming the first size pattern element.

What is claimed is:

1. A printing apparatus comprising:
a printing head including a nozzle configured to discharge ink, the printing head being configured to perform a scan to discharge the ink from the nozzle in accordance with movement in a predetermined direction; and
a control unit configured to control the printing head to print a test pattern on a printing medium, for inspecting a state of ink discharge by the nozzle, wherein
the test pattern includes a pattern element formed by a plurality of dots of the ink,
the control unit causes the printing head to print the test pattern where a number of the dots forming the pattern element on a second printing medium is smaller than a number of the dots forming the pattern element on a first printing medium, the second printing medium being more susceptible to bleed-through of the ink than the first printing medium, and
the control unit causes the printing head to print the test pattern where a number of the scans for printing the pattern element on the second printing medium is fewer than a number of the scans for printing the pattern element on the first printing medium.
2. The printing apparatus according to claim 1, wherein
the control unit causes the printing head to print the test pattern where a discharge rate of the ink by the nozzle for printing the pattern element on the second printing

17

medium is lower than a discharge rate of the ink by the nozzle for printing the pattern element on the first printing medium.

3. The printing apparatus according to claim 1, wherein when printing the test pattern by a relative movement between the printing head and the printing medium, the control unit causes a velocity of the relative movement to be the same as a velocity of the relative movement when performing normal printing. 5

4. The printing apparatus according to claim 1, wherein the control unit causes a waveform of a drive signal used to drive the nozzle when printing the test pattern to be the same as a waveform of a drive signal used to drive the nozzle when performing normal printing. 10

5. A printing method comprising:
a printing step of printing a test pattern on a printing medium, using a printing head including a nozzle configured to discharge ink, for inspecting a state of ink discharge by the nozzle, the printing head being con- 15

18

figured to perform a scan to discharge the ink from the nozzle in accordance with movement in a predetermined direction, wherein

the test pattern includes a pattern element formed by a plurality of dots of the ink,

the printing step causes the printing head to print the test pattern where a number of the dots forming the pattern element on a second printing medium is smaller than a number of the dots forming the pattern element on a first printing medium, the second printing medium being more susceptible to bleed-through of the ink than the first printing medium, and

the printing step causes the printing head to print the test pattern where a number of the scans for printing the pattern element on the second printing medium is fewer than a number of the scans for printing the pattern element on the first printing medium.
